UNITED STATES PATENT OFFICE.

CHARLES CASSIOUS WARNER, OF CLEBURNE, TEXAS.

ARCH SUPPORTER.

Application filed July 17, 1928. Serial No. 293,364.

The present invention relates to improvements in foot appliances and has reference more particularly to an arch supporter that can be readily and easily inserted within an ordinary shoe for disposition beneath the foot of the wearer.

One of the important objects of the present invention is to provide an arch supporter which includes a main body portion and 10 auxiliary portions attached to the under side of the arch engaging portion of the main body for attaining the desired height or thickness of the foot appliance, in order to properly support the arch of the wearer.

15 Still a further object is to provide a foot appliance of the above mentioned character, wherein the uppermost auxiliary layer has its edge portions not connected to the under side of the main body for the purpose of receiving removable inserts.

20 Still a further object is to provide an arch supporter of the above mentioned character, wherein the superposed layers gradually decrease in length from the topmost to the low- 25 ermost layer, the ends of each layer being skived.

Still a further object is to provide an arch supporter of the above mentioned character which is simple in construction, inexpensive, 30 strong and durable, and further well adapted to the purpose for which it is designed.

Other objects of the invention will become apparent as the nature of the invention proceeds and when taken in connection with the 35 accompanying drawings, forming a part of this application, and in which drawings:

Figure 1 is a top plan view of the arch supporter embodying my invention.

Figure 2 is a longitudinal sectional view 40 taken approximately on the line 2—2 of Figure 1.

Figure 3 is a transverse section taken on the line 3—3 of Figure 1.

Figure 4 is a bottom plan view showing 45 ovoid or elliptical shaped inserts positioned between the bottom face of the main body and the free end portions of the uppermost layer.

Figure 5 is a detail perspective view of 50 one of the inserts.

Figure 6 is a bottom plan view of one of the inserts, and

Figure 7 is a cross sectional view, taken 55 approximately on the line 7—7 of Figure 6.

In the drawings, wherein for the purpose of illustration is shown the preferred em-

bodiment of my invention, the numeral 1 designates generally my improved arch supporter, the same comprising the body portion 2 which is formed from a single piece 60 of leather and is of such design as to permit the same to be readily inserted within an ordinary shoe.

The forward edge of the leather body is curved as illustrated at 3, so as to permit the 65 body of the support to fit directly behind the heads of the metatarsal bones of the foot.

An upwardly directed flange 4 extends from the inner edge portion of the body at the intermediate or arch engaging portion of 70 the body. The leather body is skived on its under side or base. A piece of padding of any suitable material is cemented on the upper face of the heel portion of the body as shown at 5, while a leather disc like element 75 6 of circular formation has cemented to its upper face a similar shaped padding 7 and this unit is cemented on the upper face of the forward portion of the body to provide an additional support behind the meta- 80 tarsal heads.

The invention further comprehends the provision of a plurality of layers of leather, and in the present instance, three layers are shown, the same being denoted by the reference characters 8, 9 and 10 respectively. 85 These layers are cemented together, and furthermore gradually decrease in length from the uppermost layer to the lowermost one, as clearly suggested in Figure 4. 90

The ends of each layer are skived and the uppermost layer 8 is cemented to the bottom face of the intermediate portion of the body 2, for disposition directly beneath the arch. It is to be understood that the uppermost layer 8 is secured to the bottom face 95 of the body 2, in such a manner that the edge portions of the uppermost layer are free to be spread away from the body 2, whereby to provide a wedge receiving pocket 11 at the perimeter of the uppermost layer 8, as clearly indicated in Figures 2 and 3 of the drawings and the purpose of this pocket will be presently described.

Also forming a salient part of the present 105 invention are the inserts shown at 12 in Figures 5 and 6 and these inserts are also constructed of leather and may be of any desirable shape. The edge portion of each of these inserts is skived as shown at 13, and 110 these inserts are removably positioned within the pocket 11 to act as a wedge between

the body 2 and the uppermost layer 8, and by forming the pocket completely around the edge portions of the layer 8, the inserts may be positioned at any desirable place within 5 the pockets for building up this particular portion of the arch supporter. The manner in which the inserts are positioned in the pocket is clearly illustrated in Figures 2 and 4 of the drawings.

10 While I have shown three layers as being employed for attachment to the body 2, it is to be understood that any number of layers may be used, depending upon the height that the arch supporter is to be constructed and if too great a height is formed, the layers may be removed, one by one, until the desired height is obtained, as is readily seen from the construction disclosed.

It will thus be seen from the foregoing 20 description that I have provided an arch supporter, whereby the user may make the necessary adjustments by inserting the wedges or inserts 12 between the body of the arch supporter and the auxiliary layer 25 attached to the under side thereof, so that when the arch supporter is placed in the shoe the same will insure comfort and ease to the wearer's foot, while standing, walking or running.

30 An arch supporter of this character can be manufactured at a very low cost, and will furthermore at all times be positive and efficient in carrying out the purpose for which it is designed.

35 While I have shown the preferred embodiment of my invention, it is to be understood that various changes in the size, shape and arrangement of parts may be resorted to, without departing from the spirit of the invention or the scope of the appended claims.

Having thus described my invention, what I claim as new is:

1. An arch supporter comprising a leather body adapted to fit within a shoe, a layer of 45 leather attached to the under side of the arch supporting portion of the leather body, the edges of the layer being free with respect to the adjacent portion of the leather body and inserts for removable disposition 50 between the edge portions of the layer and the leather body.

2. An arch supporter of the class described comprising a leather body adapted to fit within a shoe, a plurality of layers of leather 55 arranged in superposed relation and ce-

mented together for disposition beneath the arch supporting portion of the leather body, the uppermost layer being cemented to the bottom face of the leather body only at the central portion thereof, whereby the edge 60 portions of the uppermost layer are free, and inserts for removable disposition between the free edge portion of the uppermost layer and the bottom face of the leather body.

3. An arch supporter of the class described comprising a leather body adapted to fit within a shoe, a plurality of layers of leather arranged in superposed relation and cemented together for disposition beneath the arch supporting portion of the leather body, the uppermost layer being cemented to the bottom face of the leather body only at the central portion thereof, 70 whereby the edge portions of the uppermost layer are free, and inserts for removable disposition between the free edge portion of the uppermost layer and the bottom face of the leather body, said superposed layers gradually decreasing in length from the topmost 75 to the lowermost layer.

4. An arch supporter of the class described comprising a leather body adapted to fit within a shoe, a plurality of layers of leather arranged in superposed relation and cemented together for disposition beneath the arch supporting portion of the leather body, the uppermost layer being cemented to the bottom face of the leather body only at the central portion thereof, whereby the edge 80 portions of the uppermost layer are free, and inserts for removable disposition between the free edge portion of the uppermost layer and the bottom face of the leather body, said superposed layers gradually decreasing in length from the topmost 85 to the lowermost layer, the end portions of each layer being skived.

5. An arch supporter comprising a leather body adapted to fit within a shoe, the arch supporting portion of the leather body being thicker than the remaining portion of the leather body, said thickened portion being formed with a wedge shaped pocket beneath the bottom face of the leather body, and inserts for removable disposition within said pocket.

In testimony whereof I affix my signature.

CHARLES CASSIOUS WARNER.
